UNITED STATES PATENT OFFICE.

ERNEST MENTOR, OF NEW BRITAIN, CONNECTICUT.

SHAVING-BRUSH.

1,081,319.

Specification of Letters Patent.

Patented Dec. 16, 1913.

Application filed June 9, 1913. Serial No. 772,668.

To all whom it may concern:

Be it known that I, ERNEST MENTOR, a citizen of Sweden, residing at New Britain, in the county of Hartford and State of Connecticut, have invented certain new and useful Improvements in Shaving-Brushes, of which the following is a specification.

This invention relates to improvements in shaving brushes of the fountain type.

10 An object is to produce a device of this class in which the soap may be carried and in which a lather may be formed by agitating certain movable parts of the device.

With the foregoing and other objects in view the invention consists in the combination and arrangement of parts to be herein-after fully described in the following specification, pointed out in the claims and illustrated in the accompanying drawing which 20 forms a part of said specification and in which—

Figure 1 is a vertical section through my improved brush. Fig. 2 is a full view of the same. Fig. 3 is a cross section taken on line 3—3 of Fig. 1. Fig. 4 is a view of the soap cake used. Fig. 5 is a plan of the lather-forming brush employed.

Like reference characters indicate corresponding parts throughout the several views.

1 is the handle formed with a central longitudinal aperture through and beyond which the tube 2 extends; 3 is a cylindrical shell adapted to be screwed to the said handle and said shell is provided with a close fitting cylindrical brush 4 provided with inwardly projecting bristles 5 upon its inner periphery, the base 6 of said cylindrical brush being somewhat funnel shaped and 35 leading into a metal tube 7 provided at its free extremity with a plurality of apertures 8, said tube being disposed in the soap-dispensing brush 9 carried at the free extremity of the cylindrical shell 3.

45 The tube 2 extending through the handle 1 is provided with an apertured cap 10 at one end and at the end of the brush handle adjacent the shell said tube is encircled by a washer 11 formed with radial apertures 12, the washer 11 being disposed against the end of the said handle 1. The tube 2 passes through the said washer and shell into the cylindrical brush 4 and said tube is apertured in alignment with the apertures in the washer 11, and the lower end of said tube 50 is threaded to accommodate the nuts 13

which when in position retains the washer 14 upon said tube. Between the washers 14 and 11 the soap cake 15 formed with a central aperture is disposed about the tube 2, 60 the diameter of said cake being such as to cause frictional contact with the bristles 5 of the cylindrical brush 4. The tube 2 with its several washers and the soap cake may be reciprocated within the handle 1 and brush 4.

16 is the head for the plunger rod 17 that is movably disposed within the tube 2 and said plunger rod carries a plunger 18 at its lower extremity that fits snugly but slidably 76 within the tube 2 and that is normally disposed above the apertures in that tube, through the medium of a spring 19 seated upon a partition 20 passing through the said tube. The tube 2 is adapted to contain water 75 above the said plunger 18.

Operation: By depressing the plunger below the apertures in the tube 2 against the tension of the spring 19 the water within that tube is permitted to flow out through 80 apertures 12 of washer 11 and into the bristles 5 of the brush 4. When the brush is sufficiently moistened the tube 2 is reciprocated within the handle and brush 4, thus rubbing the soap 15 over said bristles 5 and 85 forming a lather which passes through the brush 4 into the tube 7 and out through the apertures 8 in the same into the lather-applying brush 9 by which it is applied to the face of the operator.

90 What is claimed is:—

1. In a fountain brush, an apertured handle, a shell removably secured thereto, a brush terminally carried by said shell, an apertured tube disposed within said brush, 95 a cylindrical brush disposed within said shell communicating with said apertured tube, an apertured movable tube passing through and beyond the aforesaid brush handle and partly through said cylindrical 100 brush, liquid-transmission means connecting the apertured portion of said movable tube and the said cylindrical brush, a soap cake carried by said movable tube engaging said cylindrical brush and means within said 105 movable tube for regulating the liquid flow therefrom into said liquid-transmission means.

2. In a fountain brush, an apertured handle, a shell removably secured thereto, a brush terminally carried by said shell, an apertured tube disposed within said brush, a 110

cylindrical brush disposed within said shell
communicating with said apertured tube,
an apertured movable tube passing through
and beyond the aforesaid brush handle and
5 into said cylindrical brush, a radially aper-
tured washer encircling said movable tube
in the plane of the apertured portion there-
of and communicating with the said cylin-
drical brush, a soap cake carried by said
10 movable tube engaging said cylindrical

brush and means within said movable tube
for regulating the liquid flow therefrom.

In testimony that I claim the foregoing as
my own I have hereto affixed my signature
in the presence of two subscribing witnesses. 15

ERNEST MENTOR.
